UNITED STATES PATENT OFFICE.

CHARLES W. BORG, OF MOLINE, ILLINOIS.

WOOD-PLANING MACHINE.

1,072,691.

Specification of Letters Patent.

Patented Sept. 9, 1913.

Original application filed September 7, 1906, Serial No. 333,707. Divided and this application filed January 23, 1907. Serial No. 353,663.

To all whom it may concern:

Be it known that I, CHARLES W. BORG, a citizen of the United States, residing at Moline, in the county of Rock Island and 5 State of Illinois, have invented certain new and useful Improvements in Wood-Planing Machines, of which the following is a specification, reference being had therein to the accompanying drawing.

10 This case is a division of my prior application, filed September 7, 1906, Serial Number 333,707; upon which was issued Patent No. 965,983, dated August 2, 1910. In this patent are fully described and claimed features not claimed in the present application.

The object of my invention is to provide in a single wood-planing machine, a standard jointer and a standard straight work "sticker," capable of chain or roll feed and 20 a wide range of adjustments for different lines of work.

In the drawings: Figure 1 is a front elevation of my machine; showing also parts described and claimed in the application 25 above named; Fig. 2 is a plan view of the same; Fig. 3 is a perspective detail of the feed-roll drive; Fig. 4 is a detail, partially in section, of the feed-table elevating mechanism and Fig. 5 is a detail of the feed-chain 30 drive.

The numeral 1 represents the base of the machine frame, 2 the front side of the box frame mounted on said base, 3 the rear side of said box frame, 4 and 5 the front and rear 35 ends of said box frame, 6 the vertically-adjustable shaping-table which carries and controls a bottom jointing cutter, an outside shaping cutter and the associated side presser mechanism hereinafter more fully described. Said feed table is vertically adjustable by means of an elevating screw 7 attached thereto, as shown in Fig. 1 and projecting downwardly into a standard 8 integral with or attached to the base 1. Said 40 screw is operated by means of a hand wheel 9 on a shaft 10, said shaft having at its inner end a bevel-gear 11 which meshes with a second bevel-gear 12, said gear 12 also constituting a nut for the elevating screw 7, as 45 clearly shown in Fig. 4. Said table is suitably guided in ways on the side 2 of the box frame and is clamped in its adjusted position by means of a clip 13 which contacts with a downwardly projecting support 50 14 suitably attached to the box frame, said

support 14 also providing at its upper end a bearing for the upper facing cutter hereinafter more fully described. Said table 6 supports at its forward or entering end a jointer-table section 15 having downwardly 60 projecting wedge sections 16, 16, as shown in dotted lines in Fig. 1, which wedges rest upon corresponding wedge sections 17, 17 formed at the bottom of a longitudinally arranged slot in the table 6, as will be understood from Fig. 1. The table section 15 is adjusted both vertically and longitudinally by means of a hand wheel 18 carrying a screw 19 which passes through a threaded lug 20 depending from the bottom of the 65 table 15; and the table 15 when adjusted is clamped by means of screws 21, 21, in any desired relation with the bottom or jointing cutter hereinafter more fully described. That portion of the table 6 in rear of said 70 jointing cutter, carries a friction reducing roll 22, adjustable with relation to said table, as will be understood from Fig. 1. As shown at the right of Fig. 2 said table 6 has attached thereto an adjustable side jointing 75 section 23 for receiving the blank or work-piece after it has passed the side jointing cutter hereinafter described.

The bottom jointing cutter is shown as a 80 whole at 24 and is adjustable with relation to table 6 by means of the slotted bearing 25, guides 26 and clamping nut 27 (Fig. 1). This cutter is driven by means of a pulley 28 receiving its power from a belt driven from the main counter-shaft (not shown) but attached to the floor of the shop at the right of Fig. 2 as will be readily understood.

29 indicates as a whole a top dressing cutter suitably mounted in boxes or journals 85 on the top of the main frame, as clearly shown in Fig. 2. This cutter receives power from the main counter-shaft by means of a belt passing over the pulley 31, as will be readily understood. The side jointing cutter 32 is mounted on a vertical shaft 33 and receives its power from the main counter-shaft through a belt passing over the pulley 34 with a quarter turn, as will be apparent from Fig. 2. Said jointing cutter is laterally adjustable in guides 35 secured to 90 the main frame; being carried in a journal frame 36 which may be adjusted and clamped by any desired mechanism (not shown).

The parts 37 to 50^e herein shown may be 110

used as a laterally movable shaping cutter, as described in my patent above referred to, or the cam driving mechanism may be disconnected, and the cutter 37 used as a laterally-stationary, jointing or planing cutter; as hereinafter more fully described.

The machine as a whole is provided with two feed-mechanisms, the first consisting of an endless feed chain 51 working in a horizontal plane, its front side passing through a slot in the vertical portion 52, of the feed table, said chain having a plurality of removable feed teeth 53, 53, which teeth extend through a comparatively narrow horizontal slot 54 and project into the path of the blank to be fed. The second portion of the feed mechanism of the machine comprises a series of feed rolls 57, 57, clearly shown in Figs. 1, 2 and 3, which when used for driving the blank in conjunction with the feed chain, may be toothed on their peripheries; but which rolls are removably mounted on their driving shafts so that smooth faced rolls may be substituted therefor, which smooth rolls will have a mere pressing or holding down function. Said rolls, whether toothed or plain, are mounted on shafts 58, 58, the free ends of said shafts passing through journals 59, 59, capable of vertical motion in a frame or bracket 60 suitably secured to the upper edge of the side 2 of the main frame. The opposite ends of said shafts are rotatably mounted in members 61, which are in turn pivotally mounted as at 62, 62, in brackets 63, 63, integral with or suitably attached to the top of the side 3 of the main frame, as clearly shown in Figs. 2 and 3. It will be seen that this construction permits the rotation of the feed roll shafts 58 and at the same time their independent vertical movement at the front or free ends thereof. Said feed rolls are held to their work by the following mechanism: The first feed roll; that is, the one acting first on the blank when the latter is fed into the machine, is held down by a rod 64 attached to its box 59 and passing downward through the frame member 2, said rod being pivoted at its lower end to a lever 65, which lever is in turn pivoted as at 66 to the frame member 2, and carries at its free end a weight 67 adjustable thereon for varying the pressure of said roll on the blank. The second and third rolls 57 are in turn held to their work by means of a lever 68 pivoted as at 69 to an upward extension 70 of the bracket 60; said lever 68 having adjustably secured to its outer end a weight 71. Near the pivot 69 of said lever 68 is suitably mounted an equalizing member 72 so arranged that the lever 68 bears thereon, as clearly shown in Fig. 1. Upwardly pivoted to said member 72 are rods 73 which pass downward freely through openings in the bracket 60 and are

pivotaly attached at their lower ends to the boxes or journals 59 of the second and third rolls. The purpose of this construction is to give to the primary roll 57 a comparatively light pressure upon the blank; as this roll acts upon the blank while its underside is as yet rough and not acted upon by the bottom jointing-cutter 24. After the blank has passed the said bottom jointing-cutter and proceeds over the portion of the table 6 in rear thereof and over the anti-friction roll 22, it may be held to its position on the table 6 with a comparatively greater pressure; which pressure is applied by the longer lever 68 and heavier weight 71. Passing now to the driving mechanism for said feed chain and feed rolls, this drive is effected by the train of mechanism now to be described. This train receives power from a belt driven by the main countershaft, which belt passes over a pulley 74 (Fig. 2), said pulley being mounted on a stud 75 suitably located in the side 3 of the main frame. Integral with, or suitably attached to the pulley 74 is a pinion 76 which pinion meshes with a gear 77 mounted on a stud 78 also suitably located on the frame member 3. Coaxially mounted on the same stud, and either integral with or secured to the gear 77 is a pinion 79 meshing with a gear 80 keyed or otherwise secured to the main power shaft 81. Said power shaft passes transversely through the main frame of the machine and has secured thereto first a series of sprockets 82, 83, 84. Sprocket 82 is connected by a chain 85 with a sprocket 86 secured to the shaft 58 of the third feed roll 57. In like manner sprocket 83 is connected by a chain 87 with a sprocket 88 secured to the shaft 58 of the middle or second feed roll 57; and sprocket wheel 84 is connected by a chain 89 with a sprocket 90 secured to the shaft 58 of the first or primary feed roll 57. The main power shaft 81 has also secured thereto a bevel-gear 91 (see Fig. 5), said bevel-gear meshing with a second bevel-gear 92 secured to a vertical shaft 93 which passes upwardly through the top of the member 5 of the main frame and carries at its upper end the sprocket 94 which drives the feed chain 51. Said feed chain, at its opposite end, is carried by a toothless flanged roll or carrier 95 suitably mounted on a stud 96 located in an extension of the main frame, as clearly shown in Fig. 2.

Returning to the main power shaft 81, said shaft extends beyond the bevel-gear 91 and is provided with a clutch 97; said shaft being divided within the clutch so that the extreme end thereof may be disconnected from the remainder of said shaft as will be readily understood. When so disconnected it will be seen that the parts

98 to 104 (Fig. 5) and the cam 41, will remain at rest. The cutter 37 may then be adjusted by hand and remain stationary in any desired position, so as to operate as a 5 jointing cutter, similarly to the cutter 32, already described.

The gear train which drives the main feed shaft 81 is provided with a suitable shield 105 and the belt which actuates said feed 10 train may be controlled by idlers 106, 106, mounted on a T-shaped lever or carrier 107, which carrier is pivoted on a stud 108 suitably mounted on the main frame. The third arm of the carrier 107, is connected by 15 a link or rod 109 to a lever 110 pivoted as at 111 to the box side 3 of the main frame and extending upwardly within reach of the operator where it is provided with an operating handle 112 for controlling the belt 20 tightening pulleys 106, as will be readily understood. This lever 110 and the link 109 are so mounted and proportioned that when the aforesaid lever is swung to one side of its pivot its weight will tend to hold the tighteners 106 in contact with the driving bolt; and when swung to the opposite side it will tend to hold said tighteners out of contact with the driving belt and stop the entire feed train of the machine.

30 The work guiding means, as distinguished from the work propelling means, comprises the following: On the table 15 may be adjustably mounted a plurality of studs 113 carrying leaf springs 114. The studs 113 being vertically and rotatably adjustable in the table 15 and secured in any desired position by clamping screws 115. After the work-piece has passed the bottom jointing and top dressing cutters 24 and 29 and has 40 been reduced to uniform depth and provided with smooth upper and lower surfaces, it may be further held to its path of movement by adjustable but rigid guides 116, 116, secured to the main frame and vertically movable by means of the adjusting screws 117. The work-piece after having passed the cutters 37 and 32 (the former having in this event no lateral movement), the finished piece may then be held to the vertical face 50 23 by means of an adjustable guide 118.

Operation: For jointing or "sticking" straight work, it will be readily understood that the shaping cam 41 may be held stationary by disconnecting its drive at the 55 clutch 97 (Fig. 5). The feed chain drive may be also disconnected by moving the bevel gear 91 out of contact with gear 92 and the feed teeth (or so many thereof as is necessary) may be removed from the feed 60 chain to leave clear the path of the blank which may then be driven solely by the toothed feed rolls 57; or, if preferred, both the rolls and feed chain may be used for feeding short pieces of straight work. The 65 shaping cutter may remain in contact with

the outer side of the blank so as to merely dress it in straight lines, or may be thrown altogether out of contact with the outer edge of the work.

It is apparent that many changes may be 70 made in the proportion and arrangement of parts of my machine without departing from my invention; since

What I claim is:—

1. In a wood-working machine, the combination of an initial horizontal feed table, a cutter adapted to be adjusted to have its cutting plane above the said feed table, a horizontal plane table in the rear of the cutter, means for adjusting the cutter to have 75 its cutting plane exactly in the plane of the said plane table or above said plane table as desired, a series of feed-rolls above said tables, some of the rolls of said series contacting with the blank before said blank reaches the cutter, others of the rolls of said series contacting with the blank after it has 80 passed the cutter, mechanism which holds the first rolls of the series in contact with the blank with comparatively light pressure 85 and which holds the other rolls of the series in contact with the blank with comparatively heavy pressure.

2. In a wood-working machine, the combination of a main frame, a horizontal plane table adjustably mounted thereon, a horizontal cutter arranged with its cutting plane exactly in the plane of said table and mounted on the said table, an initial feed table adjustable to a plane below the cutting 90 plane of the said cutter, means for holding the blank flatly and firmly in contact with the said plane table, a vertical plane receiving guide mounted on said main frame in the rear of said first cutter and capable of transverse adjustment, means for holding 95 the blank firmly against the said plane receiving guide, a vertical cutter arranged with its cutting plane exactly in the plane of said vertical receiving guide, a vertical feeding guide arranged to coöperate with the said vertical cutter and adjustably mounted on said horizontal plane table arranged with its blank contacting surface 100 farther removed from the longitudinal axis 105 of the blank than is the said vertical cutter, and means for holding the blank firmly and flatly against the said vertical plane receiving guide.

3. In a wood-working machine, the combination of an initial horizontal feed table, a horizontal cutter in the rear thereof and with its cutting plane adjustable above the said feed table, a horizontal plane table in the rear of the said cutter and exactly in 115 the cutting plane of the said cutter, means for holding the blank flatly and firmly against the said plane table irrespective of all other holding devices, and a feed chain 120 passing the said cutter, the said feed chain 125 130

being adapted to contact with the blank at a part perpendicular to the plane of the feed table.

4. In a wood-working machine, the combination of an initial horizontal feed table, a horizontal cutter in the rear thereof and with its cutting plane adjustable above the said feed table, a horizontal plane table in the rear of the said cutter and exactly in the cutting plane of the said cutter, means for holding the blank flatly and firmly against the said plane table irrespective of all other holding devices, a feed chain passing the said cutter, all parts of said feed chain lying in a horizontal plane a vertical feed guide, a vertical cutter arranged with its cutting plane nearer the longitudinal axis of the blank than is the vertical feed guide, a vertical plane receiving guide arranged in the cutting plane of the said vertical cutter, and means for holding the blank flatly and firmly against the vertical plane table.

5. In a wood-working machine, the combination of an initial horizontal feed table, a horizontal cutter in the rear thereof and with its cutting plane adjustable above the said feed table, a horizontal plane table in the rear of the said cutter and exactly in the cutting plane of the said cutter, means for holding the blank flatly and firmly against the said plane table irrespective of all other holding devices, and a feed chain passing the said cutter and mounted to travel with all parts in a plane parallel to the said horizontal plane table.

6. In a wood-working machine, the combination of an initial horizontal feed table, a horizontal cutter in the rear of the said feed table and adjustable to bring its cutting plane slightly above the said feed table, a plane table arranged exactly in the plane of the said cutter, controlling means for holding the blank firmly and flatly against the said plane table, subordinate means for holding the blank against the said feed table, a vertical feed table, a vertical cutter ar-

ranged in the rear of the said first cutter and with its cutting plane nearer the longitudinal axis of the blank than is the vertical feed table, a plane table arranged exactly in the cutting plane of the said vertical cutter, controlling means for holding the blank firmly and flatly against the said plane table, and subordinate means for holding the blank against the said vertical feed table.

7. In a wood-working machine, the combination of an initial horizontal feed table, a horizontal cutter in the rear thereof and with its cutting plane adjustable thereabove, a plane table in the rear of the said cutter and arranged exactly in the cutting plane of the said cutter, a feed chain mounted to pass the said cutter, feed rolls mounted to hold the blank firmly and flatly against the said feed table, and means for driving the said feed chain and feed rolls.

8. In a wood-working machine, the combination of an initial feed table, a cutter axially parallel thereto and adjustable to bring its cutting plane nearer the longitudinal axis of the blank than is the said feed table, the plane table in the rear of the said cutter arranged exactly in the cutting plane of the said cutter, a plurality of power driven feed rolls mounted above said plane table, one of said rolls being mounted above the feed table, and others of said rolls being mounted over the said plane table, means for holding the first named roll upon the blank with a comparatively light pressure, and independent means for holding all of the remaining rolls upon the blank with a heavier pressure adapted to maintain the blank firmly and flatly in contact with the plane table.

In testimony whereof I affix my signature in presence of two witnesses.

CHARLES W. BORG.
